LEE RIAL, OF LOS ANGELES, AND WILLIAM HEBERN, OF OAKLAND, CALIFORNIA.

COMBINATION-LOCK.

1,247,150.

Specification of Letters Patent. Patented Nov. 20, 1917.

Application filed December 11, 1916. Serial No. 136,203.

To all whom it may concern:

Be it known that we, LEE RIAL, of Los Angeles, county of Los Angeles, and State of California, and WILLIAM HEBERN, of 5 Oakland, county of Alameda, and State of California, citizens of the United States, have invented new and useful Improvements in Combination-Locks, of which the following is a specification.

10 This invention relates to a combination lock.

One of the objects of the present invention is to provide a simple, substantial, cheaply manufactured combination lock, 15 which, although adapted for many uses, is here shown as employed for the purpose of locking out the clutch on an automobile to render the engine useless. Another object of the invention is to provide a combination 20 lock which employs a plurality of keys, any one or any number of which may be employed in combination to open the lock. Further objects will hereinafter appear.

The invention consists of the parts and 25 the construction and combination of parts as hereinafter more fully described and claimed, having reference to the accompanying drawings, in which—

Figure 1 is a side elevation of the lock, 30 also showing the bracket by which it is secured in position.

Fig. 2 is a detail horizontal section on line 2—2 of Fig. 1.

Fig. 3 is an enlarged detail view of one 35 end of the locking plate and the bar.

Fig. 4 is a diagrammatic view, showing the application of the invention to the clutch of an automobile.

Fig. 5 is a horizontal section on line 5—5 40 of Fig. 6.

Fig. 6 is a side elevation, partly in section, showing the front plate removed.

Fig. 7 is a vertical end section on line 7—7 45 of Fig. 6.

Fig. 8 is a front view of the key plate.

Fig. 9 is a cross section on line 9—9 of Fig. 5.

Fig. 10 is a perspective view, showing the relative positions of one of the keys and 50 the key plate.

Fig. 11 is a perspective view of a part of the key plate.

Fig. 12 is a cross section of the key plate, showing one key in locking position and another in releasing position.

Referring to the drawings in detail, A in-

dicates a rectangular-shaped casing, internally of which is formed a chamber 2. This chamber is adapted to be closed from the front by a plate 3, which is secured by means of three screws, such as indicated at 4, 5 and 6. Slidably mounted internally of the casing in the chamber 2 are a key plate 7, a locking plate 8, and a spring plate 9; the spring plate 9 being slidably mounted in the direction of arrow *d* while the key plate and locking plate may move in either of the directions indicated by arrows *b*.

Formed on one end of the casing A is a cylindrical extension 10 and formed on the end of each plate 7 and 8 is a guide 11 which projects into a chamber formed in the projection 10. These guiding members support the plates at one end and are always subjected to the pressure of a spring 12 interposed between said guiding members and the end of the chamber. The opposite end of the key plate is held in position by means of a bar 13 projecting through the casing and provided with a head 14 on its outer end, while the locking plate is supported by a pawl 15 which is adapted to be moved into or out of engagement with the locking bar 16. This locking bar is provided with ratchet teeth 17, into or out of engagement with which the pawl is adapted to be moved, and it is, furthermore, provided with a head 18 and an adjusting collar 19.

The locking bar as a whole projects 90 through a cylindrical chamber 20 formed in one end of the main casing and is guided in this chamber by means of the collar 19; the bar 13 forming a stop with which the collar 19 engages to limit the upward movement of the locking bar, said upward movement being transmitted through a spring 21 interposed between the collar and the lower end of the cylindrical chamber 20.

Formed in the front plate 3 is a central 100 opening, through which projects a button 22. This button forms a part of the spring plate 9 and has formed internally thereof a cylindrical chamber which incloses the outer end of a stud 23 secured in the opposite wall 105 of the casing A. Formed on the stud, as at 24, is a collar and interposed between said collar and the end of the cylindrical chamber in the button is a coil spring 25. This spring normally exerts its pressure against 110 the button or the plate and, therefore, normally serves the function of holding the

spring plate against the inner face of the front plate 3, as shown in Fig. 5.

Formed in the spring plate is a plurality of rectangular-shaped openings 26, and 5 formed in the key plate in register therewith are similar openings 27. Extending through each pair of aligned openings is a key 28, there being in the present instance twenty pairs of aligned openings and there- 10 fore twenty keys in all, as shown in Fig. 1. Formed on each key is a pair of offset slots 29 and 30 which are adapted to be moved into or out of register with the slots in the key plate, and formed on each key is a col- 15 lar 31 which engages with the front plate on one side and the spring plate 9 on the other side; the spring 25 having sufficient tension to hold all the keys in the position shown in Fig. 7 when the lock is not being operated 20 and also having sufficient tension to return any keys that may have been pushed in, as will hereinafter be described. Each individual key is supported at one end in the front plate 3 and at the opposite end in a 25 pocket 32 formed in the inner face of the main casing A. Each individual key must, therefore, extend through the spring plate and the key plate, and as the locking plate merely consists of a comparatively narrow 30 bar, it can readily be seen that there will be no interference between the keys and said plate (see Fig. 7).

The operation of the lock will be as follows:

35 When used as a clutch lock on an automobile, its position will be approximately such as shown in Fig. 4; that is, the lower end of the bar 16 is adapted to be projected into or out of register with the clutch collar 40, as 40 shown, when this is moved into inoperative position. The lock proper may be secured to the frame or floor of the car in any suitable manner, but preferably as shown in Fig. 1. This is accomplished as follows: A 45 bar or plate 41 is first secured to the chassis or frame 42 by means of a pair of screws 43. These screws extend into a plate 44 but not entirely through same.

A covering plate 45, having a hook 46 50 formed on one end, is then placed on top of the plate 41 and two screws, such as indicated at 47, are inserted. These screws are provided with square shanks 48 at their upper ends which are adapted to be inserted 55 sidewise into the casing, as shown in Fig. 2; that is, the bottom portion of the casing is slotted to fit the shanks 48, and as the heads 49 of the screws extend into the casing it can readily be seen that it will be impossible for 60 anyone to remove the lock as a whole before the front plate 3 has been removed as said front plate, when in position, prevents the casing from being slipped off of the square shanks of the screws.

65 To release the locking bar once it has been

lowered to engage the clutch collar 40 the following operation is necessary: One or more of the keys 28 employed are normally positioned, as shown at 50 in Fig. 12; that is, the slots 29 in these particular keys are out 70 of register with the key plate and, therefore, prevent sidewise movement of the same. To bring said keys into register with the key plate or the slots 29 into register, it is first necessary to operate the spring plate 9. This 75 is accomplished by pressing the button 22 inwardly to remove the spring tension from the keys. The particular keys as previously described, whose slots 29 are out of register with the key plate are then pressed inwardly 80 as far as the recesses 32 in the inner face of the casing permit. The slots 29 will then be in register with the key plate and as the remaining keys assume a position where they are already in register, it can readily be seen 85 that the key plate may be moved sidewise in the direction of arrow e (see Fig. 6); this being accomplished by applying pressure to the head 14.

The locking plate 8 will also move in unison with the key plate against the tension of spring 12 as a pair of pins 52 is provided on the key plate for this purpose. These pins extend through slots 53 in the locking plate and movement of the key plate in the 95 direction of arrow e will naturally cause said pins to engage the ends of the slot and move the locking plate in the same direction. The pawl 15, on the end of the locking plate, will thus move out of engagement with the 100 teeth 17 on the locking bar, thus permitting said locking bar to be raised or retracted by means of the spring 21 which engages the collar 19; the upward movement of the bar 16 being limited by means of the collar 19 105 when the latter engages the bar 13. The clutch collar is in this manner released and can, therefore, function in the usual manner when the pedal 60 is operated.

The locking plate, together with the key 110 plate, will return to normal position the moment the head 14 is released, this being caused by the tension of the spring 12 which will immediately expand when the key plate is released. The slots 53 in the locking plate are sufficiently long to permit said plate to remain stationary if the pawl should not be in register with a tooth 17. A slight movement of the bar 16 will immediately cause the locking plate to move into engagement 115 the moment a register is secured. The provision of the collar 19 and the perforations 19^a permit any adjustment desired to be secured.

From the foregoing description it will be 125 remembered that the screws 43 and 47 cannot be tampered with or removed except by removing the front plate 3. This is of considerable importance as it might otherwise be possible to remove the lock as a whole. 130

In order to prevent the removal of the front plate 3 a similar novel arrangement has been provided. The screws 4, 5 and 6, which secure this plate in position, are each provided with a square shank 4^a, 5^a and 6^a, respectively. These square shank portions are formed on the screws at a point where they extend through the key plate, and as this in turn is provided with a square-shaped slot, as shown in Fig. 8, it becomes impossible to turn the screws except when the key plate is moved into releasing position. In other words, it is necessary to know the combination of the lock before it is possible to move the plate into a position where turning of the screws 4, 5 and 6 is possible to remove the front plate 3.

By referring to Fig. 7, it will be seen that each key 28 is provided with a head 28^a which is sufficiently long to extend a considerable distance beyond the outer face of the front plate 3. These heads are rectangular in shape, as shown in Figs. 1 and 7, and as it is only necessary to use two or three of the keys to open the combination; it is obvious that the constant use of the lock will soon cause signs of wear to show. This would immediately expose the combination, as anyone could readily see that these particular keys were the ones which must necessarily be operated when the lock is to be opened. To prevent the showing of any such wear, it is preferable to provide rectangular openings in the front plate 3 to such an extent that no wear can take place at this point. The rectangular collars 31 employed form a snug fit with relation to the front plate and as these are on the inside of the plate and receive all the wear, it is impossible to detect which keys are operated. Again, if any key does become worn to such an extent that it might give away the combination, it is possible to change the same at any time by removing the front plate and turning the keys over; that is, by turning the key desired to a position where the slot 30 will be lowermost and the slot 29 uppermost, any number of the keys may thus be changed and consequently the combination may be changed at any time desired.

While the lock is here shown as used for the purpose of locking the clutch collar on an automobile, it is obvious that it might be used for the purpose of locking the gears or any other part of the mechanism and also that it might be used for doors or any other purpose desired. We also wish it understood that the materials and finish of the several parts of the device are such as the experience and judgment of the manufacturer may dictate.

We wish it understood that various changes in form, proportions and minor details of construction may be resorted to

within the scope of the appended claims and that we do not wish to limit ourselves to the specific design and construction here shown.

Having thus described our invention, what we claim and desire to secure by Letters Patent is—

1. A combination lock comprising a casing, a key plate slidably mounted in the casing, a plurality of keys normally assuming a locked position with relation to the key plate to lock the latter against sliding movement, a plurality of keys normally assuming an unlocked position with relation to the key plate, the locking keys being movable to a position where sliding movement of the key plate is permitted, a spring plate normally adapted to hold the locking keys in locking position, and means for moving said spring plate to release the locking keys to permit the same to be moved to releasing position.

2. A combination lock comprising a casing, a key plate slidably mounted in the casing, a plurality of keys normally assuming a locked position with relation to the key plate to lock the latter against sliding movement, a plurality of keys normally assuming an unlocked position with relation to the key plate, the locking keys being movable to a position where sliding movement of the key plate is permitted, a plate normally adapted to hold the locking keys in locking position, means for moving the second-named plate to release the locking keys to permit the same to be moved to releasing position, and means for returning the second-named plate to simultaneously move the locking keys back to locking position.

3. A combination lock comprising a casing, a key plate slidably mounted in the casing, a plurality of keys normally assuming a locked position with relation to the key plate to lock the latter against sliding movement, said keys being movable to a position where sliding movement of the key plate is permitted, a front plate forming a closure for the casing, said plate having openings formed therein through which one end of each key extends, screws securing said plate to the casing, and a shank formed on each screw with which the key plate is engageable to secure the screws against turning movement.

4. A combination lock comprising a casing, a key plate slidably mounted in the casing, a plurality of keys normally assuming a locked position with relation to the key plate to lock the latter against sliding movement, said keys being movable to a position where sliding movement of the key plate is permitted, a front plate forming a closure for the casing, said plate having openings formed therein through which one end of each key extends, screws securing said plate

to the casing, each screw having a shank with which the key plate is engageable to secure the screws against turning movement, and a plurality of screws extending 5 through the casing to permit the casing to be secured to a support said casing having slots formed therein through which the second-named screws extend, and each second-named screw having a flattened shank and 10 head on each screw positioned interiorly of the casing and inclosed therein by the front plate.

5. The combination with a casing having a locking mechanism mounted therein, of a 15 front plate inclosing said mechanism secured to the casing, and a plurality of screws extending through slots formed in one side of the casing to permit the latter to be secured to a support, each screw having 20 a flattened shank and head thereon to secure it against turning movement, said heads and shanks being positioned interiorly of the casing and inclosed by the front plate.

25. 6. A combination lock comprising a casing having a chamber formed therein, a front plate forming a closure for said chamber, a key plate having a plurality of openings formed therein slidably mounted 30 lengthwise within the chamber, said front plate having openings formed therein positioned in alinement with the openings in the key plate, a plurality of keys slidably mounted in the casing at right angles to 35 the key plate, said keys extending through the openings in the front plate and key plate and there being one key for each pair of alined openings and each key having a slot formed therein which when in alinement 40 with the key plate permits sliding movement thereof, each individual key being movable to bring the slotted portion thereof into or out of alinement with the key plate, and means extending through said 45 front plate exteriorly of the casing for moving the key plate.

7. A combination lock comprising a casing having a chamber formed therein, a front plate forming a closure for said chamber, a key plate having a plurality of openings formed therein slidably mounted 50 lengthwise within the chamber, said front plate having openings formed therein positioned in alinement with the openings in the key plate, a plurality of keys slidably mounted in the casing at right angles to 55 the key plate, said keys extending through the openings in the front plate and key plate and there being one key for each pair of alined openings and each key having 60 a slot formed therein which when in alinement with the key plate permits sliding movement thereof, each individual key being movable to bring the slotted portion 65 thereof into or out of alinement with the

key plate, means extending through said front plate exteriorly of the casing for moving the key plate, and a locking plate having a pawl formed on one end adapted to move in unison with the key plate. 70

8. A combination lock comprising a casing having a chamber formed therein, a front plate forming a closure for said chamber, a key plate having a plurality of openings formed therein slidably mounted lengthwise within the chamber, said front plate having openings formed therein positioned in alinement with the openings in the key plate, a plurality of keys slidably mounted in the casing at right angles to 80 the key plate, said keys extending through the openings in the front plate and key plate and there being one key for each pair of alined openings and each key having a slot formed therein which when in alinement with the key plate permits sliding movement thereof, each individual key being movable to bring the slotted portion thereof into or out of alinement with the key plate, means extending exteriorly of 85 the casing for moving the key plate, a locking plate having a pawl formed on one end adapted to move in unison with the key plate, and a locking bar extending through the casing adapted to be engaged by the 90 pawl and locked against movement.

9. A combination lock, comprising a casing, a key plate slidable therein; a plurality of keys operatively associated with said key plate, to control its sliding movements, certain of said keys occupying an unlocking position with relation to said plate to permit its movement, and certain other keys, depending upon the combination of the lock, normally assuming a locked position with 100 relation to the plate to prevent such movement but movable to a position to release said plate; all of said keys being removably and reversibly mounted to permit a new group of keys to be positioned for locking 105 action, so as to change the combination of the lock at will; a plate normally adapted to hold the locking keys in locking position; means for moving the second-named plate to release the locking keys to permit the same 110 to be moved to releasing position; and means for returning said second-named plate to simultaneously move the locking keys back to locking position. 115

10. A combination lock, comprising a casing; a key plate slidable therein and formed with a plurality of openings; a plurality of keys, one for each opening, extending through said openings and provided each with a pair of separate notches adapted for 120 alternative co-action with the corresponding opening, to control the sliding movements of said plate, certain of said keys occupying a position wherein their active notches align with said openings so as to permit the move- 125 130

- ment of said plate, and certain other keys, depending upon the combination of the lock, normally assuming a position wherein their active notches are out of alinement with said 5 openings and prevent such movement, the last-named keys being movable to bring their said active notches into such alinement; all of said keys being removably and reversibly mounted to permit the active relation of the notches of any selected key to the corresponding opening to be changed, thereby to change the combination of the lock at will; a plate normally adapted to hold the locking keys in locking position; 10 means for moving the second-named plate to release the locking keys to permit the same to be moved to releasing position; and means for returning said second-named plate to simultaneously move the locking 15 keys back to locking position.
11. A combination lock, comprising a casing; a key plate slidable therein and formed with a plurality of openings; a plurality of keys, one for each opening, extending 20 through said openings and provided each with a pair of notches formed in the upper and lower surfaces thereof at points out of vertical alinement with each other, said notches adapted for alternative co-action 25 with said openings to control the sliding movements of said plate, certain of said keys occupying a position wherein their active notches aline with the corresponding openings in said plate so as to permit the 30 movement of the latter, and certain other keys, depending upon the combination of the lock, normally assuming a position wherein their active notches are out of alinement 35 with their openings and prevent such movement, the last-named keys being movable to bring their said active notches into such alinement; all of said keys being removably and reversibly mounted to permit either notch of any selected key to be brought into 40 active relation to its respective opening, thereby to change the combination of the lock at will; a plate normally adapted to hold the locking keys in locking position; means for moving the second-named plate 45 to release the locking keys to permit the same to be moved to releasing position; and means for returning said second-named plate to simultaneously move the locking 50 keys back to locking position.
- 55 12. A combination lock, comprising a casing; a key plate slidable therein; a member
- for moving said plate projecting exteriorly of the casing; a locking plate connected to move in unison with said key plate; a locking bar movable relatively to said key and locking plates into and out of locking position and normally engaged and held in such position by said locking plate; and a plurality of keys operatively associated with said key plate and normally assuming a locked position with relation to the same to prevent the sliding movement of the key and locking plates and the consequent release of said bar, but movable to a position to unlock said plates, so as to permit such movement and release. 60
13. A combination lock, comprising a casing; a key plate slidable sidewise therein; a member for moving said plate projecting exteriorly of the casing; a locking plate connected to move in unison with said key plate; a vertical locking bar movable endwise relatively to said key and locking plates into and out of locking position and normally engaged and held in such position by said locking plate; and a plurality of keys operatively associated with said key plate and normally assuming a locked position with relation to the same, to prevent the sliding movement of the key and locking plates and the consequent release of said bar, but movable to a position to unlock said plates, so as to permit such movement and release. 65
14. A combination lock, comprising a casing; a key plate slidable sidewise therein; a member for moving said plate projecting exteriorly of the casing; a locking plate connected to move in unison with said key plate and provided with a pawl; a locking bar movable at right angles to said key and locking plates into and out of locking position and provided adjacent said pawl with a series of teeth for interchangeable engagement thereby, to hold said bar in its locking position; and a plurality of keys operatively associated with said key plate and normally assuming a locked position with relation to the same, to prevent the sliding movement of the key and locking plates and the consequent release of said teeth from said pawl, but movable to a position to unlock said plates, so as to permit such movement and release. 70

In testimony whereof we have hereunto set our hands.

LEE RIAL.
WILLIAM HEBERN.
